JOSIAH LETCHWORTH, OF BUFFALO, NEW YORK.

Design No. 4,202, dated July 5, 1870.

DESIGN FOR A TRACE-SUPPORTING STUD.

The Schedule referred to in these Letters Patent and making part of the same

I, JOSIAH LETCHWORTH, of the city of Buffalo, in the county of Erie and State of New York, have invented and produced a certain new and original Design for a Trace-supporting Stud for Harness, of which the following is a specification.

My design relates to a trace-support of peculiar construction, invented by me, which is attached to the back strap over the horse's hip to support and keep the traces off of the ground, when they are detached from the whiffletree.

It is composed of a plate, provided with slots or loops at its edges for the attachment of the back-strap, crupper, and lazy straps, from the center of which plate projects upward a stud or pin, over which are engaged the cock-eyes at the end of traces.

The design, as shown in the drawings, consists in constructing the central part of such or similar catches of the shape and figure of a horse's head, which not only constitutes a handsome and appropriate ornament for the place it is designed to occupy, but the form of the device, owing to the projection of the nose, ears, and mane, is such as to render it peculiarly adapted to prevent the accidental disengagement of the cock-eyes therefrom.

In the accompanying drawings—

Figure I represents a side elevation of my design, and

Figure II, a plan thereof.

Like letters of reference designate like parts in each of the figures.

A is the plate of my improved catch, cast with four loops, b c d d, for the respective attachment thereto of the back-strap, crupper, and lazy straps of the harness.

H is the central projection, representing a horse's head.

The shank h of the device, below the mane i, may be made round, or nearly so, and should be of sufficient height to permit of the arrangement thereon, one above the other, of the two cock-eyes at the end of the traces.

The part representing the mane should be constructed to project backward, so as to form a shoulder, as shown in the drawings at i.

The catch being attached to the harness with the face of the design in front, the cock-eye is engaged over the device H by holding the trace with the cock-eye toward the front, which is passed over it in an obvious manner, the natural shape of the head, with the tapering form of the back or mane portion on the device, conforming, to a certain degree, with the shape of the opening of the cock-eye, as the latter is being arranged thereon in the manner just described.

By making the device H of a size to barely permit of the engagement of the cock-eye, the peculiar form of the device, with the mane projecting at the rear, the nose in front, and the ears at the top, in connection with the position which the cock-eye naturally assumes, after it is arranged over it, is such as to render it almost impossible for the cock-eye to become accidentally disengaged, which can only be accomplished by a reversal of the peculiar movement by which it was connected therewith.

I claim as my invention—

The design of a horse's head for the top of a trace-supporting stud, as hereinbefore shown and described.

JOSIAH LETCHWORTH.
